UNITED STATES PATENT OFFICE.

BENJAMIN F. CAMPBELL, OF PLACERVILLE, COLORADO.

RAILWAY-TIE.

969,459.

Specification of Letters Patent. Patented Sept. 6, 1910.

Application filed January 18, 1910. Serial No. 538,623.

To all whom it may concern:

Be it known that I, BENJAMIN F. CAMPBELL, a citizen of the United States, residing at Placerville, in the county of San Miguel, State of Colorado, have invented certain new and useful Improvements in Railway-Ties; and I do hereby declare the following to be a full, clear, and exact description of the invention, such as will enable others skilled in the art to which it appertains to make and use the same.

This invention relates to metal railway ties, and has for one of its objects to improve the construction and increase the efficiency and utility of devices of this character.

Another object of the invention is to provide a simply constructed device of this character whereby the rails may be adjustably supported upon the tie, and the rails held firmly from movement, and thus maintained in position to resist the severe strains to which devices of this character are subjected.

With these and other objects in view, the invention consists in certain novel features of construction as hereinafter shown and described and then specifically pointed out in the claims; and, in the drawings illustrative of the preferred embodiment of the invention, Figure 1 is a side elevation of one of the improved ties with the rails in position thereon and in transverse section, Fig. 2 is a plan view of the same, Fig. 3 is a longitudinal section on the line 3—3 of Fig. 2, Fig. 4 is a transverse section on the line 4—4 of Fig. 2, Fig. 5 is a perspective view of the adjustable rail clamp detached.

The improved device comprises a base or body 10, preferably channel shaped transversely, whereby a horizontal bottom and vertical side members are produced, as shown. The base is preferably rolled or pressed from plate steel of suitable strength, and is formed with a depressed intermediate portion whereby terminal projections 11 are produced at the ends, the inner portions of the projections overhanging as shown at 12. The rails represented at 13 are designed to bear upon the upper edges of the side members with their base flanges at one side bearing beneath the overhangs 12, as shown. By this means the outer edges of the rails are maintained in position, and prevented from upward movement. Slidably located within the base member 10 are substantially U-

shaped locking members 14, the sides of the locking member bearing against the sides of the vertical webs of the member 10 and the connecting portion of the U-shaped member 60 bearing upon the upper face of the bottom portion of the base, as shown. The sides of the U-shaped member 14 project upwardly as shown at 15 and with their inner ends overhanging at 16 to bear over the inner edges of the base flanges of the rails. 65

In the sides of the member 10 at the points where the rails 13 bear upon them are formed longitudinal slots 17 through which clamp bolts 18 pass, the clamp bolts also 70 passing through the sides of the member 14. The clamp bolts are provided with heads 19 at one end and clamp nuts 20 at their other ends, and also provided with jam nuts 21. By this means the member 14 may be 75 clamped in position relative to the base member 10, and adjusted longitudinally of the latter within the range of the slot 17.

Extending transversely of the member 14 and within the same near its ends are combined stay bars and adjusting bolt guides 22, the stay bars being rigidly secured to the sides of the member 10, preferably by rivets 23, as shown. Extending between the sides of the member 14 are similar combined 85 stay bars and adjusting bolt guides 24, preferably secured in place by rivets 25. Extending through the members 22—24 are relatively heavy bolts 26, each having a head 27 at one end and carrying a clamp 90 nut 28 at the end, and preferably provided also with jam nuts 29. By this simple means the members 14 may be forcibly adjusted outwardly to clamp them against the base flanges of the rails, and thus rigidly 95 support the rails in position. The bolts 26—18 thus coact to rigidly support the rail, and prevent displacement. By this arrangement also it will be obvious that any looseness which may occur between the 100 parts owing to the severe concussions and pounding action to which the rails are subjected, may be readily "taken up," by simply rotating the nuts 20—21 and 28—29.

The various portions of the device except 105 the clamp bolts are formed of plate metal, preferably of steel, and pressed or bent into the required shape, and may be galvanized or otherwise coated to prevent corrosion.

What is claimed is:—

1. A railway tie comprising a body having spaced vertical sides and with upwardly

110

directed projections near their ends, said projections overhanging at their inner ends, U-shaped clamp members slidable between the sides of said body and with upward projections overhanging at their inner ends, said overhanging portions adapted to bear over the base flanges of the rails, tie bars extending between the sides of the said body, tie bars extending between the sides 10 of said clamp members, and clamp bolts operating through the tie bars of the body and the adjacent tie bar of the clamp members.

2. A railway tie comprising a body having spaced vertical sides with longitudinal slots and provided with upwardly directed projections near their ends, said projections overhanging at their inner ends, U-shaped clamp members slidable between the sides of

said body and with upwardly directed projections overhanging at their inner ends, 20 said overhanging portions adapted to bear over the base flanges of the rails, tie bars extending between the sides of said body, tie bars extending between the sides of said clamp members, clamp bolts operating 25 through the tie bars of said body and the adjacent tie bars of the clamp members, and clamp bolts operating through the sides of said clamp members and through the slots of said body.

In testimony whereof, I affix my signature, in presence of two witnesses.

BENJAMIN F. CAMPBELL.
